SLIDE-FASTENED CLOSURE CONSTRUCTION
FOR RIGID CONTAINERS

Neil A. Fowler, River Forest, Ill., assignor to General Box Company, Chicago, Ill., a corporation of Delaware

Application October 9, 1940, Serial No. 360,433

8 Claims. (Cl. 217—72)

This invention relates to slide-fastened closure constructions and, in particular, to the provision of new and improved slide-fastened closure constructions for containers or the like, such as shipping containers, hogsheads, mothproof cabinets, etc., which are formed of rigid, inflexible materials.

It is an object of this invention to provide such a closure construction wherein a pair of cooperating slide-fastened stringers are fixed to relatively rigid members at opposite sides of the closure-opening, which stringers may be readily and conveniently coupled and uncoupled by the use of a slider or other coupling device or tool for detachably connecting the members together to provide a convenient, quick operating closure.

It is a further object of this invention to provide such a closure construction wherein the slide fastener is protected from abrasion and other damage upon contact of the container or the like with supporting surfaces or other objects, and wherein adequate clearance is provided for ease and convenience of operation of the slider or other coupling device or tool in opening and closing the closure.

These and other objects and advantages of the invention will appear from the following description taken in conjunction with the accompanying drawings which form a part thereof, and will be pointed out in the appended claims.

In the drawings:

Fig. 1 is a view, in perspective, of a closure construction according to this invention as applied to a known type of tobacco hogshead, the closure being shown in open position and the parts of the hogshead disassembled;

Fig. 2 is a view similar to Fig. 1, but showing the closure closed and the parts of the hogshead assembled;

Fig. 3 is a fragmentary detail, in perspective, of the hogshead illustrated in Figs. 1 and 2;

Fig. 4 is a section taken substantially on the line 4—4 of Fig. 2;

Fig. 5 is a section taken substantially on the line 5—5 of Fig. 1;

Fig. 6 is a view similar to Fig. 4, but showing a former type of closure construction over which my invention is an improvement;

Fig. 7 is a fragmentary detail, in perspective, illustrating a preferred manner of attachment of the slide-fastened stringers to the hogshead staves, as shown in Figs. 1, 2 and 4;

Fig. 8 is a view similar to Fig. 6, illustrating a modified form of attachment;

Fig. 9 is a fragmentary detail, in perspective, illustrating a second modification; and

Fig. 10 is a view similar to Fig. 8, illustrating a third modification.

5 Formerly, in the construction of containers formed of relatively inflexible materials, it was believed to be necessary to secure together the relatively rigid members at opposite sides of a closure by mechanical, inflexible, though sometimes articulated, devices. Particular examples existed in packing cases, casks and hogsheads constructed of relatively inflexible materials such as wood, plywood, or the like, encircled by tension wires or bands, which were secured together by riveting, twisting, by the provision of end loops receiving separate fastening means such as connectors each comprising a short length of wire extending in common through the two end loops of each wire and with its ends twisted upon themselves to complete the continuity of the tension wires, as well as by various other known connecting means.

25 Where such constructions were utilized in a container such as the illustrated tobacco hogshead, it was necessary in disassembling the hogshead that a difficult, inconvenient and time-consuming operation be performed on each wire, which operation was likewise necessary in, thereafter, re-assembling the hogshead.

30 According to the principles of this invention, the above objects are achieved with obviation of the above-described disadvantages by the use of a pair of cooperating slide fastener stringers attached to substantially rigid members at opposite sides of a container closure opening and substantially coextensive with the length of the opening. The term "rigid" as herein used is relative, and the term "rigid members" refers to members of wood, plywood, fiber board, composition board, and the like as distinguished from flexible tapes, leather, textile materials and the like, wherein no substantial difficulties of attachment of slide fasteners are encountered.

45 As shown in Figs. 1, 2 and 3, the illustrated container embodying the principles of my invention is a tobacco hogshead comprising generally a pair of similar and interchangeable head members 11, a pair of complementary mats 12 and 14 forming the side walls of the container, and a pair of end hoops 15 extending about the end portions of the mats 12 and 14 and compressively retaining these end portions of the mats 12 and 14 firmly against the head members 11 disposed therewithin.

50 55 Each mat comprises a plurality of staves 16,

each of which is provided at opposite ends with an attached head retainer block 17 having grooves 17a at each side for a purpose which will hereinafter more clearly appear. The staves 16 of each mat are connected by a plurality of tension wires 18 which are secured thereto by staples 19.

As shown in Fig. 6, it was a prior practice to provide each tension wire 18 with loops 18a at each end and to connect these loops by means of a connector 18c comprising a short length of wire similar to the wire from which the tension wires 18 were formed, which connector member 18c was twisted upon itself at 18d, as shown in Fig. 6, to provide a continuation of the tension wires 18 of each mat in order that the tension wires 18 of each mat with their pair of connector members 18c should form a closed loop extending about the respective staves 16 of the mats forming the side walls of the hogshead.

According to this invention, the above-described structure of Fig. 6 is eliminated and the ends of the tension wires 18 are anchored to the end staves 16a of each mat in suitable manner and by suitable means as, for instance, by insertion through an aperture 16b provided in each end stave 16a, the extremities 18b of the tension wires 18 being bent over upon the inside of each end stave 16a, as shown in Figs. 4 and 5.

In this manner the mats 12 and 14 are formed as units comprising a plurality of staves 16 secured together by the substantially semi-circular tension wires 18 having their ends anchored to the end staves 16a of each mat, as described above. The tension wires 18 provide a relatively flexible connection between the staves of the mats, enabling them to be drawn about the heads 11 of the hogshead, as shown in Figs. 1 and 2.

The heads 11 each comprises a flat substantially circular member 20 having secured at one side an inwardly offset circular flange member 21 extending about the periphery and forming a peripheral step 22 which is adapted to be engaged by the head retainer blocks 17 at each end of the respective staves 16, as shown in Fig. 3. The grooves 17a of the head retainer block 17 engage the outer surface of the flange 21 and enhance the gripping between the head retainer blocks 17 and the head members 11 in addition to making the side surfaces of the blocks 17 more nearly arcuate.

While it is preferable, in many cases, that the mats 12 and 14 shall be independent of permanent attachment to one another, each mat having a slide fastener stringer at each side edge, in order that they may be handled with greatest convenience, nevertheless they may be hingedly connected at one edge, as shown in Figs. 1 and 5, and detachably connected at the other edge by a slide fastener, as shown in Figs. 1 and 4.

The hinge construction shown in Figs. 1 and 5 for which a second slide-fastened closure may be substituted, as explained above, comprises a wide hinge strip 23 of duck, canvas or other suitable strong flexible material disposed substantially centrally of the adjacent edges of the end staves 16a and secured to the end staves 16a by rows of stitching 24 extending through the hinged strip 23 and the staves 16a, which staves are formed of wood, plywood, or the like, as described above. As the hinged strip is disposed outside the stave 16a, the mats 12 and 14 may be folded over upon one another with their outside surfaces together, for convenience in handling and shipping.

The closure construction, at the opposite edges of the mats 12 and 14, is shown in Figs. 1, 2 and 4. This closure construction includes a pair of slide fastener stringers of conventional form each comprising a tape 25 having a reinforced edge 26, upon which is secured a row of predeterminedly spaced interlock fastener members 27. Each tape 25 may be provided with one part of a separating end fitting 28, as shown in Fig. 8, although it is preferable that this end fitting be eliminated, as shown in Figs. 1, 2 and 7, in order to obviate the necessity for complete alignment of the end staves and attached closure parts adjacent the closure of the container.

15 The tape 25 may be formed of a strip of strong flexible material of sufficient width to permit the use of plural rows of heavy stitching substantially removed from the rows of fastener members 27, but I find it possible to use a slide fastener stringer of conventional narrow width by providing extensions 29 comprising strips of strong flexible material such as duck or canvas secured to the stringer tapes 25 by rows of stitching 30, the outer edge portions of stringer tape extensions 29 being secured by rows of stitching 31 to the end staves 16a through which they extend. Those portions of the tape extensions 29 between the innermost row of stitching 31 and the interlocking fastener members 27, along with the stringer tapes 25, provide flexible supports for the rows of interlocking fastener members 27 which are unattached to the underlying portions of the end staves 16a.

35 It is preferable that a fastener member receiving channel be provided underlying the rows of fastener members and as shown in Fig. 4, each end stave 16a may be provided at its edge with a groove 32 underlying the rows of interlocking fastener members 27, these grooves 32 being complementary to form a channel 33 underlying the rows of interlocking fastener members, whereby the fastener members are permitted to move inwardly beyond the plane of the outer surfaces of the end staves 16a upon encountering exterior forces or objects.

45 In addition this channel 33 facilitates sliding movement of a slider 34 or other coupling device, as shown in Fig. 7, longitudinally of the interlocking fastener members 27 and the supporting end staves 16a in such manner as to prevent binding and catching of the slider 34 or other coupling device between the fastener member supports and the end staves 16a of the mats 12 and 14.

55 As an alternative to the attachment of the stringer tape extensions 29 to the end staves 16a by the rows of stitching 31, these rows of stitching 31 may be eliminated and the tape extensions 29 attached to the underlying portions of the end staves 16a by other means such as nails, staples, etc., or preferably by means of relatively inflexible strips 35 secured over the tape extensions 29 by means of nails 36 or other suitable fastening means, as shown in Fig. 8. Preferably where a separating end fitting 28 is provided at the lower ends of the stringer tapes 25, as shown in Fig. 8, the end portion of at least one of the strips 35 is mitered, as shown at 37, to provide ultimate flexibility adjacent the tape extension ends in order to facilitate manual access to the separating end fitting 28. As shown in Fig. 8, each tape extension 29 is provided at its outer edge with a marginal edge seam or hem formed by turning the edge portion of the strip 75 over upon itself to form three plies united by a

line of stitching 42. These hems 41 abuttingly engage the outer edge of each inflexible strip 35.

If desired, a metallic channel member 39 provided with marginal flanges 39a may be substituted for the above-described strips 35, as shown in Fig. 9, the nails or other fastening means being inserted through the central portion of the channel 39 between the flanges 39a, which portion overlies the marginal side hem 41. Thus the marginal edge seam or hem 41 is confined between and abuttingly engages the flanges 39a of the channel 39. This attachment of the stringer tape extension 29 to the end staves 16a effectively prevents tearing of the tape extension by the nails 36 upon the application of great stresses such as are encountered in tobacco hogsheads of the type illustrated, which are adapted to contain substantially one thousand pounds of leaf tobacco under substantial compression.

Another satisfactory manner of attaching the stringer tape extensions 29 to the end staves 16a is illustrated in Fig. 10. This construction is similar to that illustrated in Fig. 8, except that the end stave 16a is provided with channels 43 and cooperating splines 44 of substantially complementary form, the attachment of the strips 35 by the nails 36 effectively maintaining the splines in position, whereby they cooperate with the channels 43 effectively to clamp the tape extensions 29 against movement relative to the underlying supporting end staves 16a.

From the above description, it will clearly appear that I have provided a new and improved slide-fastened closure construction for containers such as shipping containers, hogsheads, etc., which are constructed of relatively inflexible or substantially rigid materials and wherein the closure opening is of substantial length. An extreme example of the difficulties encountered in utilizing a flexible slide fastener in securing together relatively inflexible or substantially rigid closure defining members is found in the illustrated hogshead which is adapted to contain substantially one thousand pounds of leaf tobacco under substantial compression for long periods of storage.

In the normal sequence of tobacco handling, the following steps are followed:

(1) Leaf tobacco is bought at auction rooms in baskets.

(2) The tobacco is transported in the baskets to a packing shed.

(3) A tobacco hogshead is set up with one head removed to receive tobacco.

(4) The tobacco is transferred from baskets to hogsheads, in which it is packed under hydraulic pressure. In small markets, hand presses are used instead of hydraulic presses. Each hogshead is completely closed by attachment of the top head, and the tobacco is ready for transportation.

(5) The hogshead, and the contained tobacco, is shipped to a tobacco re-drying plant.

(6) The slide fastener is opened and the hogshead stripped from the enclosed tobacco in the re-drying plant.

(7) Each "hand" of tobacco removed from the stripped hogsheads is placed separately upon drying sticks which are carried by continuous conveyors through conditioning machines, where the tobacco is first heated to drive off all moisture and then brought to uniform predetermined moisture content in the moisture chamber of the conditioning machine.

(8) The hogshead is re-assembled and the

slide-fastened closure is closed to prepare the hogshead for receiving conditioned tobacco.

(9) The conditioned tobacco is packed in the re-assembled hogshead under hydraulic pressure.

(10) The top head of the hogshead is inserted and the end band placed over the staves completely to close the hogshead.

(11) The hogshead is placed in storage for a period of from two to four years.

(12) After the storage period, the hogsheads are removed from storage and taken to vacuum sweating machines in a stemmery.

(13) Each hogshead is "cracked" at the sides for ventilation by opening the slide-fastened closure between the hogshead end staves without disturbing the heads and end bands.

(14) The "cracked" hogshead is put into a vacuum machine where it is subjected to extreme vacuum, followed by injection of steam to soften and humidify the tobacco in the "cracked" hogshead.

(15) The hogshead is removed from the vacuum machine, stood on end and stripped from the steamed mass of tobacco by removal of the end bands, heads, and mats from the tobacco mass.

(16) The dis-assembled hogshead parts are removed in knock-down form for storage or re-use.

(17) The tobacco proceeds through the stemming machines where stems are removed and thence through various steps of cigarette manufacture, etc.

From the above summary, it will clearly appear that the slide-fastened closure is closed in step 3, then opened in step 6, thereafter closed in step 8, and then, again, opened in step 13. These four operations are each accomplished with great convenience and facility by a simple manual operation. In these operations, the interlocking fastener members 27 are twice coupled and twice uncoupled. Where the old construction of hogshead, as illustrated in Fig. 6, is used, it is necessary in each of the closing operations of steps 3 and 8 to insert between the loops 18a of each band 18, wire coupling members 18c which must be manually bent over at 18d. Thus, each closing operation constitutes eight difficult and time-consuming manual operations, the time element being far greater than that necessary for performing the closing operations of steps 3 and 8, where the slide-fastened closure construction of this invention is utilized in a hogshead construction. Likewise, in the accomplishment of the opening operation of steps 6 and 13, eight separate time-consuming manual operations must be accomplished where the old hogshead construction is used, as compared with a single, quick and easy operation where a hogshead is constructed according to this invention, which latter operation would consume less time than any of the other eight separate operations. Likewise, the opening and closing of the slide-fastened closure is accomplished without destruction of material such as wire, and this feature alone is of considerable importance due to the high cost of wire suitable for forming the members 18c.

From the above description, it will clearly appear that the handling of such bulky masses of leaf tobacco is extremely difficult and the provision of a slide-fastened closure, according to my invention, embodies a substantial advance over the prior art hogshead construction.

Where a hogshead is provided, as described above, with one or more slide-fastened closures according to this invention, it is merely neces-

sary in stripping the hogshead from the enclosed tobacco, to remove an end hoop 15, uncouple the fastener members 27 and thereafter to spread the end staves 16a at the bottom and lift the mats and the remaining head upwardly from the tobacco.

In re-assembling the hogshead, it is merely necessary to invert the mats and the single attached head and, by the use of a suitable coupling means, to re-couple the fastener members 27. Thereafter, conditioned tobacco may be re-packed in the hogshead and the hogshead may be closed by inserting the second, or top, head and attaching the corresponding end hoop 15. Since the end hoops 15 retain the ends of the fastener stringers together, accidental opening of fasteners is totally prevented, because the ends of the stringer tapes are thus securely clamped between the end hoops 15 and underlying staves 16 and effectively retained against separation, independently of stresses applied in the tapes through the outward pressure applied by the enclosed tobacco upon the mats.

It is, of course, to be understood that the above description is merely illustrative and in nowise limiting and that I desire to comprehend within my invention such modifications, as are included within the scope of the appended claims.

Having thus fully described my invention, what I claim as new and desire to secure by Letters Patent is:

1. In a container, a pair of substantially abutting rigid members defining opposite edges of a closure and forming a fastener member receiving channel, a pair of complementary slide fastener stringers including flexible tapes having thereon rows of spaced interlocking fastener members engageable and disengageable for connecting and disconnecting said stringers, a flexible tape extension on each of said stringer tapes comprising a flexible strip of relatively strong material fixed thereto, and means securing to said rigid members portions of said flexible tape extensions spaced from said rows of interlocking fastener members, said fastener member receiving channel underlying the connected rows of interlocking fastener members upon connection of said stringers to accommodate said fastener members while providing clearance for a slidable coupling device for connecting and disconnecting said stringers, said means securing said flexible tape extensions to said rigid members comprising strips of relatively inflexible material secured over the outer edge portions of said extensions and nails extending through said last-named strips through said extensions and into said rigid members.

2. In a container, a pair of substantially abutting rigid members defining opposite edges of a closure and forming a fastener member receiving channel, a pair of complementary slide fastener stringers including flexible tapes having thereon rows of spaced interlocking fastener members engageable and disengageable for connecting and disconnecting said stringers, a flexible tape extension on each of said stringer tapes comprising a flexible strip of relatively strong material fixed thereto, and means securing to said rigid members portions of said flexible tape extensions spaced from said rows of interlocking fastener members, said fastener member receiving channel underlying the connected rows of interlocking fastener members upon connection of said stringers to accommodate said fastener members while providing clearance for a slidable coupling device for connecting and disconnecting said stringers, said

means securing said flexible tape extensions to said rigid members comprising a hem at the outer edge of each tape extension, a metallic channel member overlying each flexible tape extension, said channel member having inwardly extending flanges at each edge engaging underlying tape extension, one of said flanges abutting said hem, and fastening means projecting through the offset portions of said metallic channel members intermediate said inwardly extending flanges, said fastening means extending inwardly through said flexible tape extensions and into said rigid members.

3. In a container of the class described, a pair of rigid end members, a mat extensible about said end members and comprising a plurality of rigid longitudinal members and tension wires disposed transversely of said longitudinal members and connecting said members, said tension wires being anchored to the rigid members at each end of said mat and said last-named rigid mat members defining a closure opening, and a pair of cooperating slide fastener stringers each attached to one of said last-named rigid mat end members and connectible to close said closure opening and retain said mat about said first-named rigid end members.

4. In a tobacco hogshead, a pair of circular head members, a pair of complementary mats forming the side walls of said hogshead, each of said mats comprising a plurality of staves connected by tension wires anchored to the end staves of said mats, and slide-fastened closure means detachably connecting adjacent edges of said mats, said slide-fastened closure means comprising a pair of complementary slide fastener stringers including flexible tapes having thereon rows of spaced interlocking fastener members engageable and disengageable for connecting and disconnecting said stringers, a flexible tape extension on each of said stringer tapes comprising a flexible strip of relatively strong material fixed thereto, and rows of stitching extending through said flexible tape extensions and the underlying staves to secure to said staves portions of said flexible tape extensions spaced from said rows of interlocking fastener members.

5. In a tobacco hogshead, a pair of circular head members, a pair of complementary mats forming the side walls of said hogshead, each of said mats comprising a plurality of staves connected by tension wires anchored to the end staves of said mats, and slide-fastened closure means detachably connecting adjacent edges of said mats, said slide-fastened closure means comprising a pair of complementary slide fastener stringers including flexible tapes having thereon rows of spaced interlocking fastener members engageable and disengageable for connecting and disconnecting said stringers, a flexible stringer tape extension on each of said stringer tapes comprising a flexible strip of strong material connected thereto, and means securing to the underlying staves portions of said flexible tape extensions spaced from said rows of interlocking fastener members and comprising strips of relatively inflexible material secured over the outer edge portions of said tape extensions, and staggered nails extending through said last-named strips, through said tape extensions and into the underlying staves.

6. In a tobacco hogshead, a pair of circular head members, a pair of complementary mats forming the side walls of said hogshead, each of said mats comprising a plurality of staves connected by tension wires anchored to the end

staves of said mats, and slide-fastened closure means detachably connecting adjacent edges of said mats, said slide-fastened closure means comprising a pair of complementary slide fastener stringers including flexible tapes having thereon rows of spaced interlocking fastener members engageable and disengageable for connecting and disconnecting said stringers, a flexible stringer tape extension on each of said stringer tapes comprising a strip of strong flexible material stitched thereto with cooperating parts of a separable end fitting at the lower end of said rows of fastener members, and means securing to a pair of said end staves portions of said flexible tape extensions spaced from rows of interlocking fastener members and comprising strips of relatively inflexible material secured over the outer edge portions of said extensions, and staggered nails extending through said last-named strips, through said tape extensions and into the underlying staves, one of said last-named strips having a cutaway lower end portion affording access to said separable end fitting.

7. In a tobacco hogshead, a pair of circular head members, a pair of complementary mats forming the side walls of said hogshead, each of said mats comprising a plurality of staves connected by tension wires anchored to the end staves of said mats, and slide-fastened closure means detachably connecting adjacent edges of said mats, said slide-fastened closure means comprising a pair of complementary slide fastener stringers including flexible tapes having thereon rows

- 5 of spaced interlocking fastener members engageable and disengageable for connecting and disconnecting said stringers, stringer tape extensions of strong flexible material extending laterally from said tapes and stitched thereto, and means securing to the underlying staves portions of said flexible tape extensions spaced from rows of interlocking fastener members and each comprising a hem at the outer edge of each tape extension, a metallic channel member overlying each tape extension, said channel member having inwardly extending flanges at each edge engaging the underlying tape extension and said flanges straddling and abutting said hem, and fastening means projecting through the offset intermediate portion of each of said metallic channel members and extending inwardly through the hems of the flexible tape extensions and into the underlying staves.
- 10 15 20 25 30 8. In a tobacco hogshead, a pair of circular head members, a pair of complementary mats forming the side walls of said hogshead, means detachably connecting said mats to encircle said circular head members including a pair of complementary slide fastener stringers secured to adjacent edges of said mats and connectible for securing said edges together, and end hoops encircling the end portions of the mats adjacent the head members and fixedly clamping the end portions of the fastener stringers between said end hoops and the end portions of said mats for retaining them against accidental separation.

NEIL A. FOWLER.
